GARMENT PRESSING MACHINE

George H. Rawlinson, Portland, Oreg.

Application November 30, 1935, Serial No. 52,366

Renewed February 15, 1937

11 Claims. (Cl. 223—57)

This invention relates to pressing machines, perhaps more correctly designated as ironing machines, for laundries, useful in finishing open front garments such as walter's and surgeon's coats, shirts and the like and in this specification and the claims appended thereto the word "garment" is restricted in its definition to open front garments of the character indicated.

These garments are commonly finished on a pressing machine provided with a pair of pressing jaws, the lower one of which is known as the buck, and which are placed in a generally horizontal position. Such machines require from four to six operations to press the body of a garment of the character indicated.

An object of the present invention is a machine that will finish press the entire body of a coat-like garment in one operation.

A further object of the present invention is a machine which, while pressing a garment of the character described in one operation, will give it a rounded form, more nearly like the form of a wearer than is possible with the substantially flat press of the known art.

A further object of this invention is the great saving of time and the very considerable saving of power of operation since these presses are commonly worked by compressed air, only one motor filling of which is required with my invention as against four or more with the contemporary art.

These and many other objects which will be apparent to those skilled in the use and manufacture of laundry pressing machines, will be apparent from this specification, the drawings accompanying the same, and more particularly set forth in the claims appended hereto.

Drawings form a part of and accompany this specification, in which,—

Fig. I is an elevation, partly in section on line I—I of Fig. III, showing the press elements and the garment forming buck hereinafter described and illustrating a suitable operating means for the press elements;

Fig. II is a horizontal section on the line II—II of Fig. I;

Fig. III is a section on the line III—III of Fig. I; and

Fig. IV is an end elevation looking from the left of the structure shown in part in Fig. III, except that the garment shown draped on the body form or garment forming buck in Fig. III between the press elements is on the companion buck in Fig. IV which latter has been shifted to pressing position between the press elements,

and illustrating the press elements in their closed or pressing position as hereinafter more fully described.

The drawings are illustrative only, not intended for working drawings, and are diagrammatic in part as will be apparent upon inspection.

In the drawings, 1 is a base member adapted to rest upon a floor of a factory. A frame consists of the uprights 2 and 3 which are mounted upon and made rigid with the base by the bolts 2a and 3a. The uprights 2 and 3 are tied together across the top by the channel 4, which is made rigid with the uprights 2 and 3 by the bolts 2b and 3b.

Mounted within the frame are press elements 5 and 6, the press element 5 being swivel mounted as at 7 to the upright 3 and additionally supported by springs, such as 8 and 9, to afford relative stability thereto, yet flexible enough to achieve uniform reaction over the surface of the buck 14.

The press element 6 is reciprocable with respect to the upright 2 which carries it and is supported on guides 9 and 10 working within sockets 9a and 10a and is reciprocable to pressing position under the influence of an air motor 11, working through the toggle levers 12 and 13, a construction which is so well known that it is deemed to require no further explanation except to point out that the toggle lever 12 is pivotally attached to the upright 2 by the pivot 12a and the toggle lever 13 is pivotally attached to the press element 6 by the pivot 13a and both of these elements are hinged on the pivot 11a to 35 which likewise is pivotally attached the pushrod 11b of the motor 11. For a detailed description of the motor see Patent No. 1,965,106, dated July 3, 1934. This or any other adequate air motor may be used. Upon exhaust of the air motor 11 the pressing element 6 returns to open position, Fig. I, under the influence of the spring 11d.

Positioned centrally between the press elements 5 and 6 when in their normal or open position as shown in Fig. I, is a hollow body form buck 14, more completely described in detail in my copending application, Ser. No. 90,656 filed July 15, 1936. The body form buck is so designated to distinguish it from the silhouette type 50 of pressing form commonly used in stocking finishing presses between a pair of flat press elements.

The body form buck 14 is mounted on a carriage 15 which is reciprocable on a plane nor-

mal to the plane of reciprocation of the press element 6.

Forming a part of the carriage 15 is a resilient mounting for the buck 14 comprising the springs 5 16, guide rods 17, guideways 18 and a base for the buck 19, that is movable within the guideway 18. This resilient mounting permits a lateral movement of the buck 14 when the same is contacted by the press element 6 which moves the buck 14 10 into conformable contact with the press element 5 which is shown to be accomplished in Fig. IV.

The press elements 5 and 6 have curvilinear pressing faces, highly polished as is known in the art, and are shaped to conform in every detail 15 to the surface outline of the buck 14. They are shown to be provided with heating spaces such as 51 and 61 within which live steam will be used according to the known art and no detailed description of this feature is deemed necessary.

20 Also the buck 14 will be made sufficiently rigid by internal ribbing, not shown, or in any other manner, to withstand the load imposed by the press elements 5 and 6, so that no sensible compression of the framework of the buck 14 will 25 take place. Gross pressures of from three to six thousand pounds will be required, according to the finish desired on the garment, whether or not they are starched and according to other conditions well known in the laundry art.

30 The frame of the buck 14 will preferably be covered by a perforated rubber jacket 14a and the outer surface of the rubber jacket will be covered by an air permeable fabric coat 14b, the purpose of which is more clearly explained in 35 the copending application hereinbefore referred to. A garment may be draped over the buck 14 as shown in Fig. III and brought to smooth conformity with its outer surface and fastened in place by pins such as 141 and 142 in Fig. III, 40 though it will preferably be held in place by vacuum as set forth in the copending application referred to.

The word "draped" is used in the narrow and restricted sense of smooth and close conformity 45 of a garment on the outer surface of the buck.

The carriage 15 is mounted in a bed 25, within which it is retained by the retainers 26 and 27 and is selectively reciprocable by the air motor 28 supplied with air under pressure through the 50 conduit 29 from a source not shown and selectively controlled by an appropriate valve means, diagrammatically illustrated at 30.

This diagrammatically illustrates an expansive type reciprocable cylinder and piston motor provided with a trunnion mounting at 31 and attached to the carriage 15, by the pin 32, which engages the arm 33, a part of the carriage 15.

55 Stops 34 and 35 diagrammatically illustrate means for regulating travel of the carriage 15 so that the buck 14 will be afforded close registration with the press elements 5 and 6.

The relatively movable support of the press element 5 provided by the swivel mounting 1, and the supporting springs 8, will permit the 60 buck 14 to first conform in detail to the press element 6 and later the press element 5 to move slightly if necessary to conform to the buck. This feature will also take care of any uneven compression of the rubber cover of the buck 14.

70 As shown in Figs. II and III the pressing machine is preferably constructed with two body form bucks which will be identical in outer shape and general construction, mounting and in every other way except that they are mounted near the 75 opposite ends of the carriage 15; hence upon re-

ciprocation of the carriage 15 they are alternately brought in registration with the press elements 5 and 6 which are thereupon closed upon the buck containing the garment draped as shown in Fig. III and the garment is pressed for a short period of time, twenty seconds or more, and in the meantime the operator is removing a garment previously pressed from the buck that is outside of the jaws and replacing it with a garment that will be pressed in the next operation.

It is intended that the sleeves and collars of garments shall be finish pressed on a machine of the old type prior to being draped upon the bucks of my new pressing machine, so that when the body is pressed as hereinbefore described, the finish pressing of the garment will be completed.

To facilitate pressing the garment and to improve the finish, the interior hollow of the body form buck will be in communication with a vacuum source diagrammatically represented by the 20 numeral 60 and the influence of the vacuum will be felt on the surface of the buck 14 through the fabric 14b and the rubber coating 14a through the perforations such as 81 of which a more complete description will be found in the copending 25 application hereinbefore referred to.

In considering this machine, that part of it shown to the right in Fig. I will be regarded as the back side of the machine and will set adjacent a wall in a factory; or rows of the machines 30 may be grouped with this side facing each other with a space between.

That part of it shown to the left in Fig. I will be considered the front of the machine and suitable control apparatus, not shown, will be 35 mounted thereon, consisting of valve apparatus for controlling the reciprocating carriage, the air motor 11 and the other working parts.

In using the machine the operator will step 40 from one side to the other upon which will be arranged baskets containing unfinished garments and a table upon which the finished pressed garments may be placed after removal from the machine.

As the operator finishes draping a buck that is free of the jaws, a step takes him to the control where the press is opened and the carriage reciprocated. Then the press is closed again upon the newly placed buck and the operator 50 steps to the buck that has just emerged from the machine and redrapes it after removing the finished pressed garment, repeating the operation from time to time. Thus complete safety for the operator is assured since the controls 55 cannot be reached when the operator is in position to be caught between the press elements.

I do not intend to confine myself to the structure shown, but wish to be limited only by the scope of the appended claims. What I claim as 60 new and desire to secure by Letters Patent, is,—

1. In a pressing machine, a pair of upright pressing jaws, means for opening and closing one jaw with respect to a body form buck between said pressing jaws, a buck carriage that is made 65 reciprocable in a plane normal to the movement of the jaws, a buck mounting thereon that is reciprocable in a direction normal to the direction of movement of the buck carriage and a pair of body form bucks mounted in spaced relationship on the carriage for alternate registry positioning between the jaws.

2. The combination according to claim 1 characterized by the bucks being slidingly mounted 70 for lateral movement on the carriage to permit 75

substantially uniform pressure on the body surfaces thereof by both jaws.

3. In a pressing machine, a frame, a pair of opposed upright pressing jaws mounted therein, a relatively fixed swivel mounting for one jaw and a mounting for reciprocation for the other jaw, curvilinear pressing faces for both jaws to register with and surround a buck between the jaws, a carriage reciprocable in a direction normal to the direction of movement of the said movable jaw buck mountings reciprocable across the carriage and a plurality of bucks mounted on the carriage for alternative placement in registration with the jaws.

15. 4. In a pressing machine, a pair of duplicate garment forming bucks, a reciprocable carriage upon which the bucks are mounted, buck mountings reciprocable across the carriage, a pair of oppositely faced pressing jaws between which 20 the bucks are movable into and out of pressing relationship to the jaws, means for working one jaw and means for reciprocating the carriage.

25. 5. A pressing machine for open front garments, comprising a body form buck adapted to hold a garment in draped position thereon, opposed press elements shaped to substantially enclose the buck and form press a draped garment thereon, a relatively fixed mounting for one press element and reciprocable power operated mounting means for the other press element, a carriage for the said buck that is adapted to reciprocate the same into and out of pressing position between the press elements and an auxiliary carriage for the buck on the first named carriage that is movable under the influence of the power operated press element to bring the buck into registry with the relatively fixed press element.

30. 6. The combination as characterized in claim 5 and including a spring sustained swivel mounting for the relatively fixed press element.

35. 7. The combination as characterized in claim 5 and including automatic means for positioning the buck substantially midway between the press elements upon release of pressing force by the 40 power operated press element.

8. In a pressing machine of the character described, a pair of pressing jaws, body form bucks alternately registrable with the jaws, a main carriage for the bucks that is reciprocable in a direction normal to the direction of movement of the jaws and a pair of cross carriages mounted on the main carriage that are reciprocable at substantially right angles to the plane of movement of said main carriage.

10. 9. A garment press comprising a pair of concave faced opposed vertical jaws, a pair of conforming bucks mounted for alternate placement between the jaws, a reciprocating main carriage for the bucks and a separate cross slide carriage for each buck that is arranged to permit lateral movement of the buck under the influence of pressing movement by the jaws and automatic means for moving the buck away from one of the jaws after pressing.

15. 10. In a garment forming pressing machine of the character described, a plurality of garment forming bucks, fixed and movable enclosing pressing jaws, a main carriage upon which said bucks are mounted for movement into and out of midposition between the jaws and individual 20 auxiliary automatic buck carriages mounted on the main carriage effective to carry a sustained buck into contact with the fixed press jaw under the influence of the movable jaw and move the buck away from said fixed jaw upon cessation 25 of pressing force by the said movable jaw.

20. 11. In a pressing machine, a base, spaced vertical beams made rigid with the base at their lower ends, a tension member made rigid with the tops of the beams to define a space between 30 the beams and beneath the tension member, opposed concaved face pressing jaws that are respectively operatively mounted on opposite vertical beams to engage a buck therebetween and react against the beams, a plurality of convexed 35 pressing bucks that are mounted for movement into and out of registry between the jaws and displaceable rubber sheaths on the bucks to equalize pressure between the surfaces of the jaws and a buck in registry therewith.

40. GEORGE H. RAWLINSON. 45
